BEDDING ELEMENT

Mary N. Meredith, Toledo, Ohio

Application February 10, 1958, Serial No. 714,216

3 Claims. (Cl. 5—352)

My invention relates to bedding and particularly to 15 a bedding element which provides an occupant with mattress supporting area within a bedstead.

In summary, the invention provides means and elements, including those elements comprising said means, by which a pair of individual mattress bodies, disposed in side-by-side relation on a bedstead, are held against lateral movement relative to each other by a mattress body articulating means which permits independent compression of each mattress body, without causing compression of the other mattress body or without causing the upper surface of the other mattress body to be drawn down or to become inclined toward the compressed mattress body. Hence, the invention takes a step toward solving a problem of obtaining, for occupants of a double bed, the same degree of comfort inherent in separate and single bed use.

My invention has for its primary object to provide a bedding element for a double bed comprising a pair of articulated mattress bodies whereby one occupant of the bed does not effect a compression of the mattress body under the other occupant of the bed. A more specific object to provide means for articulating a pair of mattress bodies, which means is of such design as to engage the mattress bodies at points remote from the regions of articulation of the mattress bodies.

An even more specific object of the invention is to provide means in engagement with each of a pair of mattress bodies and operative when the mattress bodies are on a bedstead and occupied, to hold the mattress bodies in interengaging articulation on the bedstead but when unoccupied allowing each of the mattress bodies to be turned over to bring what was a lower side up and what was an upper side down and thus to obtain longer and more even wear of the mattress bodies.

Another of the more specific objects of my invention is to provide a means in engagement with each of a pair of mattress bodies serving the objects enumerated above and which by its design enables the upper surfaces of the mattress bodies to be effectually integrated whereby the mattress bodies may be easily converted from a bedding element having disintegrated independently operative mattress bodies so far as compression thereof is concerned for double occupancy to an integrated conventional double width mattress for single occupancy.

Still another of the more specific objects of my invention is to provide a means as aforesaid which constitutes an improvement over the prior art, particularly as represented by United States Letters Patent Nos. 2,651,788, 2,113,286 and 1,730,965.

My invention has for further objects those of providing other advantageous structures and arrangements which will appear from the following description and from an examination of the accompanying drawings. Bedding elements embodying my invention may take various forms. I have selected preferred and modified forms thereof to describe hereinafter and show in said

2

accompanying drawings since the preferred of these forms presently appears to me to be the best mode by which my invention may be carried out. In describing these forms, I shall use specific terms and make reference to 5 specifically shown parts in the accompanying drawings. However, by such description or reference, I do not mean to imply that variations from the forms so described or illustrated are considered by me to be beyond the contemplation of my invention made manifest herein.

10 Fig. 1 of the accompanying drawings is a perspective view illustrating the preferred form of a bedding element embodying my invention selected to illustrate the invention and shown in a position of contemplated use on a bedstead.

Fig. 2 of the said drawings illustrates a view of a section taken along the plane of the line 2—2 indicated in Fig. 1.

Fig. 3 of the accompanying drawings illustrates a plan view of the bedding element shown in Fig. 1 showing parts extended.

Fig. 4 of said drawings is a view, like Fig. 3, of a modified form of bedding element.

Fig. 5 of the accompanying drawings is an end view of the bedding element of Figs. 1, 2 and 3 when the same has been converted for conventional single occupancy.

My invention attacks the problem arising when occupants of different weight occupy the same bed at the same time. As is well known, the occupant of heavier weight causes the mattress on the bed on that side of the bed to be compressed more than that caused by the occupant of lighter weight. As a consequence, a depression of greater depth is formed in the mattress beneath the occupant of heavier weight and the upper surface of the mattress beyond said depression is drawn to incline more or less sharply toward said depression. The other or more lighter occupant, reclining on this inclined upper surface the mattress, tends to roll toward and against the other occupant, usually to the discomfort of both occupants.

Various remedies have been proposed to overcome this problem. It has been suggested that the mattress contain resilient members of greater resistance to compression on the side of the bed on which the heavier occupant contemplates reclining. It has also been suggested that two separate mattress bodies, enclosed in a envelope, one of which bodies being made to contain resilient members proportioned in their resistance to compression in accordance with the contemplated occupants' 50 weights, be used.

These attempts at solving the problem have not proven successful. That is so because my predecessors have failed to recognize that the ticking forming the area of the mattress on which the occupants recline, or the bed-pad or bottom sheet which covers the ticking, act as cross-ties between the two sides of the bed and occupants reclining thereon, so that the motion of one occupant or the effect of compression of the mattress induced thereby, is transmitted to the other occupant or the mattress or mattress area on which such other occupant reclines through such ticking, bed pad or bottom sheet.

Structures embodying my invention, on the other hand, provide a separate mattress body for each occupant and join them together to prevent lateral movement relative to 65 each other in a way and by a means that does not transmit the motion or effect of compression of one mattress to the other mattress, said means allowing the use on each mattress body of an individual bed-pad and bottom sheet thus further insuring against transmission through those mediums.

70 Turning to the forms of construction shown in the

accompanying drawings, each has a pair mattress bodies 10 and 30, that are connected, see Figs. 3 and 4, by a web marked 40 in Fig. 3 or 140 in Fig. 4.

As shown, the mattress bodies 10 and 30 are identical in size and make up and are each substantially as long as a bedstead 11 which is dimensioned for double occupancy. Each mattress body is substantially as wide as one-half the bedstead 11. The mattress bodies 10 and 30 are supported in side-by-side relation in the bedstead 11 by conventional structural means on the bedstead that forms no part of my invention and thus is not here described nor illustrated in detail.

Each mattress body may have an enveloping ticking 12 enclosing a plurality of suitable helical spring parts 13. A pad 14 and a pad 15 at opposite ends of the plurality of spring parts 13 are provided. The pads 14 and 15 may be formed of cotton, curled hair, sponge rubber or any of the number of well known padding materials.

The spring parts 13 and pads 14 and 15 serve to distend the ticking 12. When so distended, the ticking 12 takes on thickness presenting opposite facing surfaces 16 and 17, side edges 18 and 19 and end edges 20 and 21. Thus, should a weight be applied to one of the surfaces 16 and 17 of one of the mattress bodies sufficient to overcome the yielding resistance of the spring parts 13, the mattress body will be compressed.

If desired the number of spring parts 13 or the temper or gauge thereof may be varied or proportioned to resist any given weight, so that each mattress body may be individualized to fit or withstand the weight of the contemplated user, most comfortably to that user. Having opposite and like surfaces 16 and 17, each mattress body may be used with either surface up and may, as is customary in housekeeping, be turned over occasionally.

In embodiments of my invention, the mattress bodies 10 and 30 are connected together by a web. Preferably, the web is formed of fabric. In the form shown in Figs. 1, 2, 3 and 5 of the accompanying drawings, the web 40 connecting the mattress bodies is a fabric sheet whose dimension in one direction is equal to the length of a mattress body. The web 40 may, if desired, be a laminated sheet and be quilted, as padding is commonly formed. It has two opposite parallel extending edges 45 and 46. One edge 45 engages, as by being sewn or otherwise affixed to, one of the side edges 18 and 19 of one of the mattress bodies 10 and 30 and the other edge 46 of the web 40 engages in like manner to one of the sides 18 and 19 of the other mattress body.

Preferably, the edges 45 and 46 of the web 40 are affixed to the side edges of the respective mattress bodies along a line extending parallel to and mid-way between the surfaces 16 and 17. This allows for reversing the mattress bodies to bring either surface upper-most not withstanding their interconnection, as will be later explained.

The dimension of the web 40 between the edges 45 and 46 is critical to my invention. This dimension should not be substantially less than the combined widths of the mattress bodies 10 and 30. Preferably, the dimension of the web between edges 45 and 46 is substantially equal to the combined width of the mattress bodies plus halves of the thicknesses of the mattress bodies.

In the form shown in Fig. 4 of the accompanying drawings, the web 140 consists in fabric strips 141 and 142 that are arranged in criss-cross relation and may be stitched together in the area, indicated 143, at which the strips cross each other. The ends of the strips provide edges that may be sewn or otherwise affixed to the side edges of the mattress bodies. Thus, the strip 141 has an end edge 145a and an opposite end edge 145b and the strip 142 has an end edge 146a and an opposite end edge 145b.

The end edges 145a and 145b of strips 141 and 142 engage, as by being sewn or otherwise attached to, one of the side edges 18 and 19 of one of the mattress bodies

10 and 30. Preferably, the end edge 145a of strip 141 engages the side edge of the mattress body along a line parallel to and mid-way between the surfaces 16 and 17 of the mattress body in a region close to that at which the side edge of the mattress body so engaged joins one of the end edges 20 and 21 of the mattress body. Also, preferably the end edge 145b of strip 142 engages the same side edge of the mattress body engaged by end edge 145a of strip 141 along a line parallel to and mid-way between the surfaces 16 and 17 of the mattress body but in a region close to that at which the mattress body side edge so engaged joins the other of the end edges 20 and 21 of the mattress body. So also are the end edges 146a and 146b of the strips 141 and 142 connected to the other mattress body to produce a structure like that shown in Fig. 4 of the accompanying drawings.

The distance between the end edges 145a and 145b and 146a and 146b measured along lines intersecting and extending normal to the lengthwise axes of the mattress bodies engaged by said end edges is not substantially less than the combined widths of the mattress bodies. Preferably, such distance, is substantially equal to the combined widths of the mattress bodies plus halves of the thicknesses of each of the mattress bodies. Thus, the strips 141 and 142 provide a flexible fabric spider or grill like web 140 that, dimensionally speaking, is equivalent to the fabric sheet web 40.

In assembly of the mattress bodies 10 and 30 on the bedstead 11 in contemplation of double occupancy use, the mattress bodies are each placed in side-by-side relation, with side edges 18 and 19 of the mattress bodies that are engaged by the edges of the web 40 or 140, as aforesaid, outermost with respect to the bedstead 11. The web 40 or 140, as the case may be, will, by reason of such disposition of the engaged side edges of the mattress bodies, be drawn fairly taut to span the area defined within the bedstead. The "free" side edges of the mattress bodies, that is those not engaged by the web edges, become positioned in abutting articulated relation, as is shown in Figs. 1 and 2 of the accompanying drawings. The mattress bodies are held against lateral movement from this described position and relation by the web 40 or 140 without, however, any limitation being exerted on either mattress body to individually react to compression and be immune from the effect of compression of the other mattress body.

In making up a bed utilizing a bedding element embodying my invention, if mattress pads are to be used, each mattress has an individual pad, such as mattress pads 22 and 32 shown on mattress bodies 10 and 30, respectively. Likewise, each mattress body has an individual bottom sheet, such as the bottom sheets 23 and 33 shown on the respective mattress bodies 10 and 30. Thus, the make-up of the bed, so far as mattress pads and bottom sheets are concerned, is such as to preserve the independency of the mattress bodies in compression movements.

All bedding above the bottom sheet is of conventional dimension and arrangement. For example, a top sheet 100 and blanket 101 dimensioned and placed to cover both mattress bodies is used. Thus, it will be seen that my invention does not intrude upon or diminish whatever advantages there may be in double-bed use by two occupants. On the other hand, the motion or weight of one occupant of the bed tending to compress the mattress under such occupant will not be transmitted to the mattress under the other occupant thereby to disturb the other occupant.

When it is desired to turn the bedding element over, each mattress body, after removal of the other bedding, 70 may be pivoted as is diagrammatically shown in broken line 102 in Fig. 2 of the accompanying drawings, about an axis provided along the respective lines of engagement of the web therewith so that the assembly is fully extended, as shown in Figs. 3 and 4 of the accompanying

drawings. The entire assembly is then turned over, the mattress bodies are caused to pivot about each of said axes to again locate the free side edges in articulated abutting relation with each other and now with whatever surface 16 or 17 was previously up being down and the other surface up.

Should it be desired to convert the bedding element of my invention having the preferred form of web 40 for single occupancy, the mattress bodies may be pivoted to full extension as when contemplating reversal. Instead of turning the assembly over, however, the web 40 is raised in the bedstead 11 to allow the mattress bodies 10 and 30 to be inserted under the web and so that their free side edges meet along an approximately central line through the bedstead beneath the web 40. In that relation, the mattress bodies engage and are supported on the bedstead, as shown in Fig. 5 of the drawing. The web 40 will be above and cover the mattress bodies 10 and 30 bridging the abutting free side edges thereof.

Thus, my invention not only solves a problem that has long remained unsolved but also provides a mattress bedding element of considerable adaptability.

I claim:

1. A bedding element for a double bed bedstead comprising the combination of a pair of mattress bodies and a web, each mattress body having opposite facing occupant supporting surfaces and opposite and parallel extending side and end edges, the mattress bodies being of substantially equal dimensions and of a length substantially equal to the longer dimension of a bedding space within a double bed bedstead and each of a width substantially equal to one-half the width of a bedding space within a double bed bedstead; the web comprising a quilted sheet fabric having a length dimension substantially equal to the length of a mentioned mattress body and a width dimension substantially equal to the combined widths of the mentioned mattress bodies plus the thickness of one of the mentioned mattress bodies, the sheet fabric having each of its long edges in engagement with one of the mentioned mattress bodies along a line that extends along one side edge of the mattress body and

substantially parallel to and midway between the opposite facing occupant supporting surfaces of the mattress body whereby the mattress bodies are connected together and, when moved towards each other around the lines of engagement thereof with the web, the mattress bodies side edges not engaged by the web meet in abutting relation and the web is drawn taut to hold the mattress bodies against relative lateral movement.

2. A bedding element comprising a pair of mattress bodies and a web, each mattress body having opposite facing surfaces and lengthwise extending side edges, each mattress body being of the same dimension lengthwise as the lengthwise dimension of the other mattress body, said web being in engagement with one lengthwise extending side edge of each of said mattress bodies and being substantially of the same effective dimension between said mattress bodies as the combined crosswise dimensions of the two mattress bodies whereby the web extends across one of the said surfaces of both mattress bodies and tends to hold the mattress bodies against lateral movement relative to each other when the mattress bodies are placed side by side with their unengaged lengthwise extending side edges in abutting relation.

3. A bedding element as described in claim 2 in which the web comprises a pair of strips extending cross-wise each other, one end of each strip being in engagement with a side edge of one mattress body in a region proximate one end of the mattress body and the other end of each strip being in engagement with a side edge of the other mattress body in a region proximate the other end.
